[57] CLAIM

The ornamental design for a golf bag shoulder harness, as shown and described.

DESCRIPTION

FIG. 1 is a perspective view of a golf bag shoulder harness in condition of use showing my new design, it being understood that the broken lines are for illustrative purposes only and form no part of the claimed design;

FIG. 2 is an enlarged plan view thereof; and,

FIG. 3 is a plan view of a golf bag shoulder harness showing a second embodiment of my new design using a single chest belt with one adjustable pad.

The surfaces of the golf bag shoulder harness not shown in the drawing form no part of the claimed design.
